UNITED STATES PATENT OFFICE.

SAMUEL F. ARBUCKLE, OF DETROIT, MICHIGAN, ASSIGNOR TO MONOGRAM LENS CORPORATION, OF NEW YORK, N. Y., A CORPORATION OF DELAWARE.

HEADLAMP SHIELD.

Original application filed January 28, 1924, Serial No. 688,947. Divided and this application filed March 10, 1924. Serial No. 698,011.

This invention relates to a head lamp shield for preventing upward radiation of light rays from the lamp. My invention further relates to shielding means usable in connection with a head lamp which eliminates secondary reflection. The invention relates also to a type of shield for head lamps usable within replacement reflectors positioned within the original reflector of a head lamp. This application is a division of the copending application of Samuel F. Arbuckle and Carl P. Brockway, Serial No. 688,947, filed January 28, 1924.

The practice has arisen in the manufacture of head lamps, to employ as a means for diffusing the direct and reflected rays emerging from a reflector of a head lamp, a lens molded in such a manner that the light is refracted, the various rays intermixing in such a manner as to eliminate, to a large extent, a concentrated brilliancy of light, as observed from in front of the reflector. This method of diffusing the light beams is, however, of little value to the driver of a vehicle when the vehicle upon which the head lamp is placed is moving through heavy mist or fog, as the forwardly projected light rays, especially those direct rays travelling above a horizontal plane including the axis of the reflector, are reflected from the small particles of mist upwardly and rearwardly, thus causing a bar to vision above and around the head lamp which seriously interferes with the operation of the vehicle. There has recently arisen also, the practice of supplying a new reflecting surface to a head lamp by means of a replacement reflector placed within the tarnished or worn original reflector. In view of the fact that the lamp bulb in the replacement is necessarily of a focus in relation to the original reflector, and because of the fact that it is desirable that the replacement reflector be shallow, a portion of the light rays in a band adjacent the lower edge of the original reflector, are reflected upwardly, thus intensifying the confusion present when the vehicle is moving in fog.

One of the important objects of my invention, therefore, is to provide means for cutting off such rays of the light source in a head lamp which cause secondary reflection in fog, and thus diminishing driving efficiency. Another object is to provide means

for cutting off such light rays as will permit elimination of the lens type of light refracting means, and the use of a plain glass in front of the reflector. Another object of my invention is to provide a light shielding device which may be used in conjunction with a replacement reflector and in connection therewith, prevent the emergence of upwardly directed light rays in front of the head lamp. Still another object of the invention is to provide a light shield which may be effectively employed in connection with reflectors having surfaces which are ribbed to cause lateral reflection of the light rays and prevent what is known as glare.

Further objects are contemplated in the employment of simplified means for securing a light shielding means to a head lamp which may be manufactured at a minimum cost, and which may be adapted to any type of head lamp now in common use. Various other objects will become apparent also on consideration of a description of an embodiment of my invention and various modifications of the same, herewith presented and illustrated in the accompanying drawings in which

Fig. 1 is a vertical section through a head lamp showing the invention as applied to a lamp bulb;

Fig. 2 is a view of a modified method of attachment of the light shielding device, and

Fig. 3 is a second modification of the shield.

The invention, broadly stated, consists in the application to an electric lamp bulb or similar light source within the reflector of a head lamp, of a light impervious shield made, for example, of metal having a conformation approximately that of a sector of a sphere, and so positioned in front of the light, that light rays emerging from the light and passing in an upwardly and outwardly direction, are intercepted, the light rays passing to the reflecting surfaces of the reflector, however, and those direct rays passing outwardly and downwardly being unobstructed.

A feature of the invention also is the utilization of a second shield continuous with the main shield which is adapted to prevent upward reflection from the outer rim of an original reflector when the light source is in focus with a replacement reflector positioned in the original reflector.

Another feature of the invention is the employment of a base connection when attached to replacement reflectors which will permit ready rotation and axial adjustment.

5 Referring to Fig. 1 of the drawings, there is shown a head lamp casing 10 within which is positioned an original reflector 11 and a replacement reflector 12. The casing 10 and original reflector 11 are connected by means 10 of central tubing 13, positioned in short tubes 14 and 15 integral respectively with the casing 14 and reflector 11, the tube 14 extending forwardly within the casing toward the reflector, and the tube 15 extending rearwardly toward the casing and in alignment with the tube 14. The tube 13 is movable axially within the tubes 14 and 15 by means of a screw 16 having screw-threaded connection with a lug 17 fixed to the tube 13. A spring 18 is positioned about the screw 16 and bears against the lug 17 and casing 10 to maintain the tube at the limit of movement away from the casing 10. As shown in the figure, the lug 17 has movement 25 in a slot 19 formed in the casing tube 14.

The tube 13 is adapted to carry the various contacts intermediate the lamp and the current source. There is shown an electric circuit cord 20 in engagement with a plug 21, said plug having a bayonet connection 22 with the end of the tube 13. The forward end of the tube 13 is bayonet slotted to receive the base 39 of the lamp bulb 40 or the auxiliary tube 45 which is adapted to 30 be used in connection with the replacement reflector 12. The center of this tube 45 is enlarged to form a socket 48 which is externally threaded, and adjacent its inner end, is slotted to form forwardly extending fingers 49, the ends 50 of which are outturned. The socket 48 is adapted also to form the retaining means for the replacement reflector 12.

The connection between the replacement reflector and the socket is provided for in a ring member 51 which is positioned on the socket adjacent the outturned ends 50 of the flexible fingers 49. The reflector 12 apertured at its center is adapted to be clamped 45 against member 51 by means of the nut 52 and intermediate washer 53. Additional holding means for the reflector also is provided for in a flexible annular member 54, having a flat central portion 55 and outwardly and rearwardly extending flexible plates 56, the ends of which are adapted to contact against the surface of the original reflector 11. A nut 57 positioned on the socket 48 is adapted to hold the member 54 50 in position and serve also as a lock nut member with the nut 52. It is evident that by rotating the nut 52, the member 51 is forced toward the cam surfaces 58 at the ends of the fingers 49, thus clamping the replacement reflector 12 securely in engagement on

the socket 48, and also clamping the base of the lamp in position. The forward edge of the replacement reflector 12 is also outturned to form a radial band 90 which may contact with the surface of the reflector 11, although such contact is not essential in view of the holding means previously described.

Within the reflector 12 the lamp bulb 40 is placed. The base 39 of the lamp 40 is enclosed by the halves of an axially split 75 shell 60, the thickness of the shell being approximately equal to the length of the pins projecting from the base of the lamp. The object of this construction is to permit rotational adjustment of the lamp, independent of the position of the pins which, according to conventional engineering practice, are present on the bases of all lamp bulbs. The halves of the shell 60 are connected to the shield 61 by means of side 80 straps 62, as shown in Fig. 1. The shield 61 is a shell in the form of a section of the surface of a sphere, one edge 70 of the section lying in a plane parallel to and below the horizontal plane including the axis of 85 the reflector and the light source, and the other edge 71 lying in a vertical plane transverse to the reflector axis and each point thereof, lying in a line including the light source and the edge of the replacement reflector 12. The edge 71 of the section is extended in a band 72 joining the two ends of the section and having a predetermined width such that light rays emerging from the light source will be cut off on the exposed portion of the original reflector adjacent the outer edge thereof. It is apparent from this description that there is an opening 73 intermediate the band 72 and section 61 through which light rays may emerge in 90 a forwardly and downwardly direction as indicated by the light ray 74 in the drawing.

It is pointed out that the depth of the replacement reflector 12 is less than that of the reflector 11, there being an exposed portion 100 of the original reflector 11 intermediate the glass plate 84 and the flange 90, this construction being such as has been found by investigation and experiment, to give best results with a minimum of cost and material. 105 The presence, however, of this annular reflecting exposed portion of the reflector 11 makes requisite the provision of means for preventing upward reflection from the same, inasmuch as since the source of light, when 110 a replacement reflector is employed, is moved forwardly out of the local plane of the original reflector, and, consequently, light rays striking the reflector from the lamp source will not emerge in a parallel direction, but will be deflected toward the axis of the reflector. This condition has been met in the provision of the impervious shield 72 extending below the section 61, and also by 115 the position of the shield itself, the vertical 120

edge of which, as previously indicated, lying on lines drawn from the center of the light source to the edge of the replacement reflector thereby cutting off all light rays tending to pass beyond the reflector edge.

In use the shield is positioned on the lamp bulb as shown in Fig. 1, and the lamp bulb and replacement reflector clamped in position by manipulation of the nuts 52 and 57, 10 and also where necessary, by adjustment of the screw 16. The edge 17 of the lamp shield is positioned in a horizontal plane, and when the lamp is in proper position, the center of the light source is, for all practical 15 purposes, at the focus of the replacement reflector 12. When the light source is energized, light rays will emerge in all directions. Those rays, however, passing outwardly within bounds defined by the lower 20 edge 70 and upper edge 71 of the shield 61, and rays passing downwardly within the bounds determined by the band 72 are cut off, the remaining rays being reflected from the reflector and passing out in a parallel 25 direction, or passing out downwardly and forwardly through the opening 73 to illuminate the driveway directly ahead of the lamp. It is thus seen that illumination is secured sufficient for ordinary needs, and that 30 the elimination of all rays which are projected in an upwardly direction directly from the light source as well as such rays as emerge in a forward direction in the plane of the light source is accomplished. Since 35 it is light rays of the type cut off which cause the secondary reflection and diffusion of light from ground mist and fog, the elimination of these rays permits greatly increased visibility in the operation of the vehicle under such conditions, without hindering the employment of all light which is usable for direct illumination of the passage way.

The invention has been described particularly in relation to a replacement reflector for head lamps, and in such relationship it has a well defined utility. As previously indicated, one of its important functions in this connection is to cut off such rays as would tend to be reflected from the original reflector and thus cause improper light diffusement. Moreover, in connection with the specific holding means of the shields, it is particularly adapted for easy adjustment 50 relative to the reflector. In ordinary illumination, the filament of the lamp should lie in a horizontal plane, and the edge 70 of the shield should lie in a plane approximately parallel to the plane of the lamp filament. 55 In addition, where the secondary reflector is of the type which is intended to reflect the light rays in vertical zones to eliminate glare and the necessity of employing refracting lens in front of the reflector, it is requisite 60 that the plane of the lamp filament should

have a position at right angles to the planes dividing the vertical zones of the reflector in order to get the proper light distribution. This ready adjustment of the shield holding means, as in this connection, is very advantageous.

The invention, however, is usable in connections other than with a replacement reflector. I have shown in Fig. 2, the application of the invention to a lamp bulb placed in an original reflector in the ordinary manner. In this modification, the sector 61, band 72, and the corresponding position of the lower edge 70 and upper edge 71, are identical to that of the shield construction of Fig. 1, the difference in this modification residing only in the means of attachment. Instead of providing bands engaging the base of the lamp as in the modification of Fig. 1, the holding means consists in bands 95 extending from the shield axially for a portion of the distance about the lamp bulb, the ends of the same being slightly outturned. The band 95 being flexible metal or similar material, will yieldingly hold the shield in proper position on the lamp bulb and permit the insertion of the same in the ordinary way in the original reflector of the lamp. The standard connections between the current source 20 and the lamp 40 are employed in the modification of Fig. 2.

Fig. 3 discloses a still different modification in which the lamp bulb 40 carries a shield 100 painted or otherwise fixed to the surface of the bulb in proper relationship with the lamp filament. In this modification I have shown an attaching means adapted to be employed in inserting the lamp in a replacement reflector for example, a shell, 101, opposite sides of which are split for a portion of its length, the splits terminating in holes 102 adapted to receive the pins of the lamp base, this attachment permitting, as indicated in connection with Fig. 1, a rotational adjustment of the lamp within the replacement reflector socket. The base edge 102 of the sector shield 100 of Fig. 3 is shown as lying in the axial plane of the lamp and it should be understood that it is within the confines of the invention to vary the lower limiting boundary of the reflector from the plane including the axis of the reflector, to planes beneath such axis as in Fig 1, depending upon the engineering requirements.

By the construction of the lamp shield, as above noted, there is provided means of great simplicity for cutting out light rays from a lamp which hinder visibility to the driver of a vehicle and also cause dangerous glare to a pedestrian or driver of another vehicle approaching, without at the same time materially diminishing the total illumination of the lamp. This result arises from the fact that the shield does not cut

off the light rays to the reflector, these rays being reflected outwardly without hindrance as in the ordinary lamp. By the construction described, also, an exceedingly simple means of holding a lamp shield in position, of forming a connection with a replacement reflector, and of permitting adjustment of the lamp, the shield, and the reflector relative to each other is provided which has important utility in the field to which the invention is applicable.

Various modifications of the invention, other than those indicated will be apparent to those skilled in this art, and it is therefore desired to cover the invention broadly as well as specifically as indicated by the claims hereto appended.

Having thus described my invention, what is claimed is:

- 20 1. A light shield for lamp bulbs comprising a plate in front of the bulb having a conformation corresponding to that of the bulb with a base edge below the lamp filament axis, said plate being attached directly to the lamp.
- 25 2. A light shield for lamp bulbs comprising a plate in front of the bulb and attached to and supported thereby having a conformation corresponding to that of the bulb with a base edge below the lamp fila-

ment axis, and a curvilinear upper edge bounding a surface cutting off the upper portion of the forwardly projected light rays.

3. In combination, a headlamp comprising a casing; an inner reflector within the casing; an outer reflector within the casing concentric relative to said inner reflector; a lamp bulb positioned within the inner reflector; and light shielding means attached in front of said bulb having a conformation adapted to prevent the emission of upwardly directed direct rays from the lamp bulb and upwardly directed reflected rays from the outer reflector.

4. A light shield for a lamp bulb comprising a plate adapted to be positioned in front of the bulb and having a conformation corresponding to that of the bulb, a retaining band attached to the edge of said plate and forming with said plate an aperture for the emission of light rays; and resilient arms extending from said plate, said arms being adapted to engage the lamp bulb upon which the shield is positioned and yieldably retain the shield in position.

In testimony whereof, I affix my signature.

SAMUEL F. ARBUCKLE.
